CLAIM

The ornamental design for the collapsible standing drawer unit, as shown and described.

DESCRIPTION

FIG. 1 is a front elevational view of a collapsible standing drawer unit showing my new design;

FIG. 2 is a back elevational view thereof;

FIG. 3 is a side elevational view thereof, the opposite side view being the same;

FIG. 4 is a top elevational view thereof; and,

FIG. 5 is a bottom elevational view thereof.

The criss cross shading shown partially on FIGS. 2-5 is understood to continue uniformly across the surfaces shown.
